UNITED STATES PATENT OFFICE.

WILLIAM H. HOLDORF, OF MINNEAPOLIS, MINNESOTA.

FUSE-INDICATOR.

1,337,357.

Specification of Letters Patent. Patented Apr. 20, 1920.

Application filed August 2, 1918. Serial No. 248,011.

To all whom it may concern:

Be it known that I, WILLIAM H. HOLDORF, a citizen of the United States, residing at Minneapolis, in the county of Hennepin 5 and State of Minnesota, have invented new and useful Improvements in Fuse-Indicators, of which the following is a specification.

This invention relates to a fuse indicator particularly adapted for use in connection with what are known as refillable cartridge fuses though capable of application to and practical operation with any form of fuse embodying a replaceable fuse link, or for 10 permitting withdrawal of a blown fuse link and the substitution of a new link therefor. One object of the invention is to provide an automatically operating attachment comprising a movable element which may be 15 readily seen from the exterior of the cartridge or analogous device and indicate by its position the condition of a fuse link to enable an observer to determine whether a fuse is practically intact or has become 20 blown. A further object of the invention is to provide a fuse indicator that may be easily applied to a cartridge fuse or other fuse link holding means by a very simple 25 change in construction or without material modification of the fuse link holding means 30 now commonly used.

With these and other objects and advantages in view, the invention consists in the construction and arrangement of the several 35 parts which will be more fully hereinafter described and claimed.

For the purposes of practical demonstration of the ready application and efficiency in operation of the improved indicator, one 40 form of cartridge fuse has been illustrated in the drawings, but it will be understood that the indicator is not limited in its application to this precise construction of the cartridge fuse but may be applied to any 45 fuse link holding device with which the essential movable element of the improved indicator may engage, and it will also be understood that the improved indicator may be varied in proportions and general dimensions 50 to adapt the same for practical service with various sizes of cartridge fuses and other fuse link holding means.

In the drawings:

Figure 1 represents a sectional view of 55 one form of a refillable cartridge fuse showing the improved indicator applied thereto

and the essential movable element thereof in engagement with the fuse link.

Fig. 2 represents a view similar to Fig. 1 taken through the cartridge fuse at a 60 different angle and illustrating the movable element or plunger of the indicator in horizontal section.

Fig. 3 represents a transverse vertical section of the cartridge fuse with the improved 65 indicator in set position relatively to the fuse link.

Fig. 4 represents a section similar to Fig. 1 of a portion of the cartridge fuse showing a blown link and the consequent 70 change of position of the movable parts of the improved indicator.

Fig. 5 represents a detail section of a portion of the cartridge fuse and link of a form 75 different from that shown by Figs. 1, 2, 3 and 4 and illustrating a slight modification in the structure of the improved indicator.

Fig. 6 is a detail elevation particularly showing the form of fuse link illustrated by Fig. 5 and the position of the indicator 80 relatively thereto.

Fig. 7 represents a detail section of a portion of the cartridge fuse and link of further different form and illustrating a 85 further modification of the movable element or plunger of the improved indicator to accommodate the change in structure of the link.

Fig. 8 is a detail elevation of a portion 90 of the link shown by Fig. 7 and illustrating the position of the improved indicator relatively thereto.

Fig. 9 is a detail view of the essential 95 movable element or plunger of the indicator and a portion of the casing thereof illustrating a still further modification of the plunger.

The form of the cartridge fuse illustrated 100 in the drawings embodies a cylindrical shell 5 having ferrules or heads 6 secured to opposite ends and each provided with an annular flange 7 bearing against the adjacent end of the shell 5 and also with an internally screw-threaded annular seat 8 to receive a metal fuse link attaching disk 9 and a disk closure 10 which is screw-threaded 105 to fit the seat 8 and has a central opening 11 to expose the fuse for contact or engagement of the connecting means as will be readily understood. The fuse link holding disk 9 is of less diameter than the disk closure 10 and may be readily removed from

100

105

110

and applied to the seat and when applied is held in fixed position by the disk closure 10. The fuse link 12 as shown by Figs. 1, 2, 3 and 4 has its ends removably secured 5 to the disk 9 and bent over against the outer side of the disk to dispose the extremities thereof for engagement by the adjacent disk closure 10 having an opening 11 to facilitate application and removal there- 10 of, each disk closure 10 being similarly constructed and operating in a similar manner relatively to the adjacent end of the fuse link. This fuse link 12 is reduced, as at 13, on opposite sides of the center, 15 such form of fuse link being well known and need not be further referred to in detail. The improved indicator as shown by Figs. 1, 2, 3 and 4 embodies a casing 14 with an inner closing end 15 and an outer hollow head 16 of larger diameter than the screw-threaded portion of the casing, the casing being fitted in a screw-threaded opening 17 in the shell 5. Centrally movable, through the casing is a plunger 18 20 carrying a plunger disk 19 movable in the smaller screw-threaded portion of the casing, and between the plunger disk 19 and the outer closed end 20 of the enlarged or hollow head portion 16 of the casing a spring 21 is interposed and operates to move the plunger 18 inwardly, the plunger being free to move through an opening 22 in the outer closed end 20 of the hollow head 16 and also through a screw-threaded opening 23 in the center of the inner closed end 15 25 of the reduced portion of the casing 14. The plunger 18 has an indicator disk 24 on the outer end thereof and the inner end of this plunger as shown by all of the figures, except Fig. 9, is screw-threaded, 30 as at 25, to engage the threads of the opening 23 and whereby the plunger may be locked against inward movement by rotating the same through the medium of the indicator disk 24 when it is desired to replace a blown fuse disk. As shown by Fig. 9, the inner end of the plunger 18 is smooth or the screw-threads as illustrated by the remaining figures being omitted and indicating that the said plunger will practically 35 operate or perform its intended function irrespective of the threaded structure at the inner end thereof, said threaded structure being simply an incidental feature of convenience in holding the plunger in operative position when refilling the cartridge with a new fuse, or replacing a blown fuse as hereinbefore indicated. The plunger disk 19 insures a positive operation of the plunger, said disk being fixed to the plunger, and this disk also provides a bearing for the inner end of the spring 21 and whereby the plunger is operated when released from a set position.

65 As shown by Figs. 5 and 6, a different

form of fuse link 26 is shown and provided with a central opening 27 as a weakening means, said opening being variable as to its dimensions, and to accommodate this form of link the inner end of the 70 plunger 18 is provided with a disk terminal 28 to fit over the opening, said disk terminal being of a dimension proportionate to the diameter of the opening 27. The remaining features of the modified indicator as shown by Figs. 5 and 6 are the same as in the form thereof illustrated by Figs. 1, 2, 3 and 4. Figs. 7 and 8 also show a further form of fuse link 29 which is materially reduced at the center, as at 80 30, and in this instance the inner end of the plunger 18 is formed with a yoke 31 to embrace the center of the link 30, the remaining features of the indicator structure as shown by Figs. 7 and 8 being similar to the parts hereinbefore described.

After a fuse link of the usual form shown has been applied or positioned upon the shell 5, the plunger 18 is reduced so that the inner end thereof in either of the forms 90 shown will bear against or engage the link, and this engagement of the inner end of the plunger with the link will force the indicator disk 24 outwardly from the hollow head 16 and compress the spring 21 between the plunger disk 19 and the outer closed end 20 of the said hollow head. As long as the fuse link is intact, the plunger 18 and its indicator disk 24 will remain in the position particularly shown by 95 Figs. 1 and 3, but when the link is blown, the plunger 18 is released and the spring 21 will act to force the plunger inwardly and bring the indicator disk in close contact with the outer closed end 20 of the hollow 100 head 16, as shown by Fig. 4, and by this means an inspector or observer will be enabled to readily determine that the fuse link has blown and another link may be easily replaced in the cartridge and the indicator reset as shown by Figs. 1 and 3, the plunger 18 being held out during refilling of the cartridge with a new link by engagement of the inner screw-threaded end 105 25 with the threaded opening 23, or be held 110 out manually when the form of the cartridge shown by Fig. 9 is used.

The improved indicator may be easily and cheaply constructed in view of the simplicity of the parts thereof and will be materially advantageous as a means for quickly notifying an inspector or observer of the condition of a fuse link and whereby a blown fuse link may be readily located and saving of time in refilling cartridges or in 120 125 replacing blown out fuses of other types of fuse link holding devices embodying refillable features will ensue.

The improved indicator is adapted for use with any form of fuse strip that is ar- 130

ranged for disconnection by burning out, and may be applied in any practicable position on the cartridge, or to any fuse-holding device other than the cartridge hereinbefore explained and to demonstrate one application thereof. Moreover, the improved indicator is indefinitely reusable with a number of fuse links or strips, or does not cease to be operative with the burning or blowing out of the one fuse link or strip to which it has been operatively applied. The improved device may also be applied at any point along the length of the fuse link or strip with the same efficiency in service.

I claim as my invention:

1. A blown fuse indicator consisting of a cylindrical casing removably insertable in the intermediate portion of a fuse cartridge, a spring actuated plunger mounted in and movable through opposite ends of the casing and provided with an enlarged indicating means on its outer end and an intermediate disk movable within the casing, and means within the casing engaging the intermediate disk for displacing the plunger from a set position.

2. An attachment for indicating the presence of a blown fuse consisting of a spring actuated plunger having an enlarged disk indicating means on its outer end and an intermediate movement guiding disk, the inner end of the plunger being adapted to engage a fuse device.

3. A blown fuse indicating means consisting of a casing, a plunger mounted in the casing and having an enlarged disk indicating means on the outer end thereof and the inner end free to engage a fuse device, the inner end of the plunger and the casing having coöperating means to hold the plunger outwardly in temporarily removable abnormal position during positioning of the fuse for engagement by the plunger, said plunger when normally in position in engagement with the fuse device being automatically movable to change the set position of the external indicating means to show when a fuse has been blown.

4. The combination with a refillable fuse device having a fuse therein, of a casing removably inserted in the intermediate portion of the said device and provided with a

spring actuated plunger movable through opposite ends of the casing, the plunger having an enlarged indicating means on the outer end and the inner end adapted to engage a fuse device, the plunger within the casing also being provided with a guide disk and with means engaging the disk and the outer end of the casing for automatically moving the plunger inwardly into the refillable fuse device when the fuse has blown.

5. The combination with a refillable fuse device having a fuse thereon, of a casing mounted in a portion of the said device and provided with a spring-actuated plunger having an indicating means on its outer end and the inner end free to engage a fuse, the inner end of the plunger being screw-threaded to engage a portion of the casing to hold the inner end of the plunger in cleared position relatively to the fuse applied to the device to replace a blown fuse.

6. The combination with a fuse link holding cartridge, of a casing removably mounted in the intermediate portion of the cartridge and having a plunger movable through opposite ends thereof, the plunger being provided with an enlarged flat indicating means on its outer exterior end, the opposite inner end of the plunger being free to engage a fuse link, a plunger disk on the intermediate portion of the plunger movable within the casing, and a spring surrounding the plunger between the said disk and the outer end of the casing to automatically force the plunger inwardly when the fuse link has blown, the indicating means at the outer end of the plunger being held at a distance from the outer end of the casing when the plunger is set in contact with a fuse link, the inner ends of the plunger and casing having coöperating means to hold the plunger outwardly in abnormal position when applying a new link in the cartridge.

In testimony whereof I have hereunto set my hand in presence of two subscribing witnesses.
